(57) **CLAIM**

The ornamental design for a camera as shown and described.

DESCRIPTION

FIG. 1 is a front, bottom, and left side perspective view of a camera in a first position, showing my new design;

FIG. 2 is a front view thereof;

FIG. 3 is a left side view thereof;

FIG. 4 is a rear view thereof;

FIG. 5 is a right side view thereof;

FIG. 6 is a bottom view thereof;

FIG. 7 is a top view thereof;

FIG. 8 is a bottom and right side perspective view thereof;

FIG. 9 is a front and bottom perspective view thereof;

FIG. 10 is a rear, bottom, and left side perspective view thereof;

FIG. 11 is a front, bottom, and left side perspective view thereof in a second position;

FIG. 12 is a front, bottom, and left side perspective view thereof in a third position;

FIG. 13 is a front, bottom, and left side perspective view thereof in a fourth position;

FIG. 14 is a front, bottom, and left side perspective view thereof in a fifth position; and,

FIG. 15 is a front, bottom, and left side perspective view thereof in a sixth position.

The broken lines shown represent portions of the camera that form no part of the claimed design.

1 Claim, 15 Drawing Sheets
